UNITED STATES PATENT OFFICE.

CHARLES C. AUGUSTINE, OF PHILADELPHIA, PENNSYLVANIA, ASSIGNOR TO
STEEL, VAN ROSSUM & CO., OF SAME PLACE.

HEATING-STOVE.

SPECIFICATION forming part of Letters Patent No. 410,229, dated September 3, 1889.

Application filed June 7, 1889. Serial No. 313,499. (No model.)

To all whom it may concern:

Be it known that I, CHARLES C. AUGUSTINE, a citizen of the United States of America, residing at Philadelphia, in the county of Philadelphia and State of Pennsylvania, have invented certain new and useful Improvements in Heating-Stoves, of which the following is a specification, reference being had therein to the accompanying drawings.

10 My invention relates to heating stoves or furnaces of that class in which cold air is drawn into the apparatus and directed against the heated surfaces therein and then discharged to be conveyed to any desired point.

15 The features of novelty are hereinafter pointed out in the claim.

In the drawings, Figure 1 is a vertical section through the stove or furnace on a line through the flues of the ring. Fig. 2 is a 20 tail vertical sectional view through the ring and the parts connected therewith on a line through the cold-air ports of said ring. Fig. 3 is a plan view of the ring.

In the drawings, A is the fire-pot, and B the 25 ash-pit, of any desired form. Upon the top of the fire-pot is secured the ring C. This is made of cast metal with a depending flange c for attachment to the fire-pot. The inner cylindrical body portion C' extends upward

30 in line with the fire-pot and is open at both top and bottom. The upper edge of this portion forms a bearing-flange upon which is supported the inner cylindrical dome D, closed at the top by a cap-piece d. Free communication is thus provided through the open cylindrical body portion of the ring between the fire-pot and the dome.

Outside the central part of the ring C, and concentric therewith, are two vertical flanges 40 or rims c' c², the outside one c² being of less height. These flanges are connected to each other by an approximately-horizontal annular bottom or flange 1, and to the central body part c' of the ring by the upper and lower 45 walls of the inwardly-inclined smoke flues or ports S, which extend radially outward from the central body part across the intervening open space at the points shown in Fig. 3. This construction and arrangement provide support 50 for the outer flanges or rims, smoke-flues at a point between the fire-pot and dome, and also cold-air ports p between the smoke-flues

S. The flanges c' c² support vertical concentric cylinders E E. The space between said cylinders is closed at the top by a plate e', 55 and said space communicates with the fire-pot through the flues or ports S. An opening x in the horizontal flange of the ring communicates with the smoke-pipe, and from this construction it will be seen that the course of 60 the products of combustion is through the ports S, the annular space e, and then through the port x to the smoke-pipe, and for the purpose of utilizing the heat of the products of combustion as much as possible I provide 65 vertical flue-strips f f (shown for convenience slightly out of place in Fig. 1) in said annular space on each side of the exit-port, so that the draft will first be upward from the ports S over the top of the flue-sheets and then 70 down to the exit. The cold air enters the hot-air space h from below through the ports p p of the ring C between the flues S, and during its passage through this space it is acted upon by the heat from the cylindrical 75 dome D, and also from the annular smoke-space e, which completely surrounds it. An outer inclosing-case is used, preferably, provided with exit-openings o o, and the air besides being heated in the space h is acted 80 upon in its passage through the space h'.

An important feature of my stove is the location of the fire-door in relation to the ring having the flues or ports S, and, as shown, the door is positioned below the level of the 85 ring, so that there is no liability of choking the flues by feeding too much coal, nor is there any chance of the fuel being carelessly thrown into said ports S when filling the stove. It will be noticed that the flange 1 is formed 90 with inclines w intermediate of the inclined flues S, and by reason of this construction soot and dust will not lodge in the annular smoke-space, but will fall into the inclined flues, and thence into the fire-pot. This flange 95 thus serves the twofold purpose of constituting the bottom of the smoke-space and the means for directing the soot back into the fire-chamber. I prefer to cast the ring all in one piece. The parts may be bound together 100 by brace-rods, as v, Fig. 1.

Having now described my invention, what I claim is—

In combination, the fire-pot, the dome, the

inner and outer concentric cylinders, the ring interposed between the fire-pot and the dome and cylinders, said ring being constructed with flanges for seating the cylinders and dome and
5 with flues inclining upwardly and outwardly to the smoke-space between the cylinders, with a horizontal flange extending between the seat-flanges $c'c^2$, said flange being inclined on its upper side to the flues and constituting
10 the bottom of the smoke-space and having also an exit-opening X therein, the flue-

sheets on either side of the opening, and the feed-door located in the fire-pot below the ring and the ports thereof, substantially as described.

15

In testimony whereof I affix my signature in presence of two witnesses.

CHARLES C. AUGUSTINE.
